UNITED STATES PATENT OFFICE.

THOMAS SHIPLEY, OF YORK, PENNSYLVANIA.

OILING APPARATUS.

1,250,036.

Specification of Letters Patent. Patented Dec. 11, 1917.

Application filed May 23, 1917. Serial No. 171,428.

To all whom it may concern:

Be it known that I, THOMAS SHIPLEY, a citizen of the United States, and a resident of the city of York, in the county of York 5 and State of Pennsylvania, have invented certain new and useful Improvements in Oiling Apparatus, of which the following is a specification.

The oiling apparatus or system in which my invention is comprised is designed more particularly for gas compressors of the "inclosed type" so called—that is to say, a gas compressor in which the compressor cylinder or cylinders are erected upon a base, 10 which constitutes a chamber for the crank portion of the driving shaft to which the compressor pistons are connected and from which they are driven, which chamber is sealed by suitable means to form an air tight crank case in which the crank portion of the driving shaft, together with the connections between the cranks and the compressor pistons are free to move. The ends 15 of the compressor cylinders which rest on the crank case are entirely open and fit snugly into openings formed for their reception in the top of the crank case. They are securely bolted together and the joint between them being tightly packed to exclude the outside air. The compressor cylinders thus open directly into, and communicate directly with the air tight interior 20 of the crank case, and the compressor pistons are thus free to be connected directly to their respective cranks on the driving shaft, by connecting rods which are hung at their upper ends on cross pins or pivots in their respective piston heads, and at their lower ends have the usual strap connections 25 with their driving cranks. Thus all of the bearings for that portion of the driving shaft inclosed in the crank case, together with all the connections between said shaft and the compression cylinder pistons, are 30 contained within the air tight crank case and the portions of the compressor cylinders which communicate with the same.

It is the object of my invention to provide a convenient, simple and efficient means for 35 lubricating the joints and bearings thus contained within the crank case. To this end I combine with the air tight crank case, a main oil pipe line, external to the crank case, through which the oil circulates in a 40 closed circuit completed through the air tight crank case, and including an oil reser-

voir (preferably the lower part of the crank case), a pump which draws its supply of oil from said reservoir and maintains it in continuous circulation under pressure through the pipe line and proper devices by which the oil is filtered and strained before it circulates through to line, said pipe line having a plurality of injecting nozzles which enter the crank case at proper points to discharge the oil upon the different parts to be lubricated, the excess of oil thus discharged dropping into the body of oil in the lower part of the crank case from which the pump draws its supply.

Under my invention the lubricating nozzles form the terminals of branches leading from the main line into the crank case. Each injecting nozzle has its own branch separately and independently connected to the main line, and each branch is equipped with its own cleaner fitting by which the nozzle as well as the interior of the body of the branch can be effectively kept from becoming clogged up when the apparatus is in operation, and with its own stop cock by which it may be cut out of the operating circuit without interfering either with the circulation of the oil in the main line, or with the operation of the nozzles in the other branches. It is this feature which mainly characterizes my invention.

This with other features of my invention can best be explained in connection with the accompanying drawings, forming part of this specification to which I shall now refer for a better understanding of my invention.

In said drawings:

Figure 1 is a front elevation of so much of a double cylinder inclosed compressor embodying my improvements as needed for the purposes of explanation.

Fig. 2 is a plan of the same.

Fig. 3 is an end elevation of the same looking at it from the right.

In these three figures so much of the compressor as is shown is represented in outline only, without any attempt to represent the structural details of either the compressor proper or its supporting crank case.

Fig. 4 is a vertical section partly in elevation of the compressor, taken lengthwise of the inclosed crank case and in the plane of the axes of the two compressor cylinders—the upper portions of the cylinders being broken off, as unnecessary to an understanding of the invention.

Figs. 5 and 6 are sectional elevations or views of two different forms of nozzles with their cleaner fittings attached, used at different points in the oiler system.

5 Fig. 5 is a vertical section in the plane of the vertical axis of the fitting V in one of the branches D¹¹.

Fig. 5 is a sectional elevation of the fitting in one of the branches D¹¹.

10 Fig. 7 is a section in the plane of the axis of the branch D¹² at right angles to the plane of section in Fig. 6.

Each one of the two end branches D¹¹ contains a fitting such as shown in Fig. 5. 15 Each one of the intermediate branches D¹³, D¹², and D¹¹, contains a fitting such as shown in Figs. 6 and 7, save that in branch D¹² the nozzle proper, is turned downward as indicated at 12 Fig. 4 instead of upward 20 as in the two branches D¹¹.

Referring more particularly to Fig. 4 of the drawings, 1 is the closed air tight crank case, the bottom part of which is a reservoir for the oil; 2 is the engine shaft supported therein in end and center bearings 3, 35 4, and formed with two cranks 5, 5, connected to the pistons 6 of the two vertical compressor cylinders 7, by connecting rods 8, which at their upper ends extend up 40 through the open ends of the cylinders and are attached to said pistons by joint pins 9, and at their lower ends are hung on the cranks 5 by the customary straps 10. At the points 11, 11 in the top of the crank case are nozzles for oiling the end bearings 45 of the crank shaft; at the point 12 a nozzle for oiling the center bearing of the same; and at the points 13, 13 nozzles for oiling the pivot joints between the pistons 6 and 50 the connecting rods 8. The open ends of the cylinders are seated in openings in the top of the crank case and the joints between them and the crank case are of course suitably packed. It is unnecessary here to 55 scribe the structural details of the crank case inasmuch as I have made the same together with other matters pertaining thereto the subject of a separate application for Letters Patent. It is sufficient to say here that it is 60 closed tight against the admission of air by suitable packing means at all needed points.

Referring now more particularly to Figs. 1, 2 and 3, S is a pipe connected at O to the oil reservoir in the crank case and at the 65 other end to the filter F. Interposed in the pipe S is a three way cock L the purpose of which will be presently explained. P is a rotary pump driven by a belt from the crank shaft of the compressor as indicated, 70 and communicating with the filter F through a connection K and three way cock L'. Connected to the pump is the main oil line D into which the pump discharges.

By the action of the pump the oil from

the crank case is drawn through the pipe 65 S and three way cock L into and through the filter F whence it passes strained and filtered through connection K and three way cock L' into the rotary pump P which discharges it into the line D from which the 70 oil is distributed to the injecting nozzles through branches as will be presently described. A pressure gage X is placed in the main line at the angle between the riser portion and the horizontal portion of said 75 line in which the injecting nozzle branches are located as indicated in Fig. 1, for the purpose of indicating a rise in oil pressure owing to the stoppage of any one of the nozzles, as well as to indicate that the system 80 is working properly.

Extending between and connecting the three way cocks L and L' is a by-pass E in which is interposed a strainer E'. Through proper manipulation of the three way cocks 85 L, L' the pipes S and K can be cut off from communication with the filter, and thrown into communication with one another through the by-pass E, the purpose of this arrangement being to cut out the filtering 90 pot F during the time required to open it for cleaning purposes and to divert the flow of oil to the pump around the filtering pot thus permitting the oiling system to continue uninterruptedly in action during this 95 period.

There are five branches from the main line D, designated in Figs. 1 and 2, D¹¹, D¹² and D¹³, the numerals accompanying these letters of reference corresponding to the 100 similarly numbered points in Fig. 4 at which the nozzles of the thus-designated branches project through the crank case into the interior of the same. Each branch as hereinbefore stated contains its own nozzle and 105 stop cock and cleaner fittings. These fittings are the same in both branches D¹¹, as they are the same in the two branches D¹³ and the branch D¹², although there are slight minor differences between the fittings of the 110 one group as compared with the other. The drawing in Fig. 5 represents on enlarged scale one of the branches D¹¹ with its own nozzle b and stop cock Y and cleaner fitting V in which a lateral opening is formed 115 for the reception of this terminal of the branch; and the stop cock Y is interposed in the branch between the main line D and the cleaner fitting. From the inner end of the fitting leads a pipe a to the contracted nozzle b. The pipe a in branch D¹¹ is continuous, being a short pipe which extends only part way through the vertical hole m formed for its reception in the top of the crank case, this hole extending through the 120 top to the interior of the case, and constituting a duct through which the oil discharged from the nozzle, is led to a point 125

where it can drip down upon that one of the end bearings of the crank shaft which that nozzle is to serve. The pipe *a* in branch *D*¹² being of some length and also being curved for a portion of its length is sectional, being composed of three sections; the outer and intermediate sections being united by a bushing *n* extending through the side wall of the crank case, and the intermediate and inner end curved sections being united by the usual pipe coupling *l* this section being upwardly curved in order to bring its nozzle into proper relation to the joint between the connecting rod and piston which it is designed to lubricate as indicated at the point marked 13 in Fig. 4. The cleaning device *W* in Fig. 6 consists of a flexible metallic flat ribbon-like narrow wire, preferably steel wire, of sufficient weight to prevent buckling and which may have a slight longitudinal spiral twist or other known or suitable cross-sectional conformation to render its clearing action more effective. This cleaning wire is attached at its outer end to a stem which passes out through a stuffing box in the head of the fitting *V*, and has on its end an operating handle *H*. The cleaning wire *W* is of such length that when the handle *H* is pushed in toward the fitting *V* as shown in Figs. 5, 6 the end of the cleaning wire will extend through and protrude beyond the tip of the nozzle. By means of the handle the cleaning wire can be reciprocated in the pipe and forced to and fro through the nozzle tip with the effect of dislodging any foreign matter therein. For the purpose of removing any foreign matter or clogging material that may accumulate in the pipe *a* leading from the fitting *V* to the nozzle, the fitting is provided with a pet cock *T*. To thus clean the pipe the stop cock *Y* is first closed, and the pet cock *T* is then opened, whereupon the pressure which always exists in the crank case when the machine is in action will blow to the atmosphere through the pipe *a* and the pet cock, with the effect of thoroughly purging the pipe.

The nozzle end of the pipe *a* in branch *D*¹², which enters the crank case at point 12 in Fig. 4 is bent downward as there indicated in order to bring it into proper proximity to, and position above, the central crank shaft bearing which it is to serve.

Having described my improvements and the best known way to me of carrying the same into practical effect—what I claim

herein as new and desire to secure by Letters Patent is as follows:

1. In a gas compressor of the type specified, the combination with the air tight crank case and the compressor cylinders supported on and opening into said crank case, and the driving shaft and crank mechanism and connections contained in said case for operating the compressor pistons, of the following elements namely: a main oil pipe line external to the crank case; a plurality of independent branches leading therefrom into the crank case to the several parts contained therein which require lubrication, each branch being provided with its own oil injecting nozzle, cleaning device for the same operated from the exterior of the crank case, and stop cock interposed between the cleaning device and the main line, the excess of oil ejected from said nozzles dropping into the lower part of the crank case, which constitutes a reservoir to receive it, and the arrangement being such that the oil circulates through said main line in a closed circuit completed through said branches and the crank case; and a pump interposed in the main line between the oil reservoir and the branches from the main line, which draws its supply of oil from the oil reservoir and maintains it in continuous circulation under pressure through the pipe line and the crank case, substantially as and for the purposes hereinbefore set forth.

2. The combination with the elements of the combination recited in claim 1, of a filter interposed in the main line between the oil reservoir and the pump, substantially as set forth.

3. The combination with the closed crank case, and oil reservoir, the main line, and the pump, of a plurality of independent branches; in each branch a nozzle; a cleaner fitting; a pipe connecting the cleaner fitting and nozzle; a cleaning wire extending through the cleaner fitting and pipe connecting the said fitting and nozzle and adapted to reciprocate back and forth through said pipe and nozzle; an operating stem and handle for thus-operating the cleaning wire; and a pet cock carried by and communicating with the interior of the cleaner fitting; and stop cocks, one for each branch, interposed in said branch between the cleaner fitting and the main line, substantially as and for the purposes hereinbefore set forth.

In testimony whereof I affix my signature.

THOMAS SHIPLEY.
